UNITED STATES PATENT OFFICE.

SAMUEL L. ADELSON, OF NEW YORK, N. Y.

PROTECTIVE SOCKET.

1,348,620.

Specification of Letters Patent. Patented Aug. 3, 1920.

Application filed May 9, 1919. Serial No. 295,830.

To all whom it may concern:

Be it known that I, SAMUEL L. ADELSON, a citizen of the United States of America, residing at New York city, county and State 5 of New York, have invented certain new and useful Improvements in Protective Sockets, of which the following is a full, clear, and exact description.

This invention relates to a device for the 10 prevention of the removal of electric light bulbs excepting by those authorized to do so; in other words, my improved device is intended to prevent the stealing of such bulbs. To carry out my invention, I provide 15 an auxiliary socket to receive a bulb, arranged to engage a standard socket, and means to prevent the manipulation or rotation of the socket after it has been connected up for use.

I will now describe my invention in detail, and refer to the accompanying drawing, forming part of this specification, wherein:

Figure 1 is a sectional view of my invention illustrated as applied to a standard 25 socket, said socket being illustrated partly in section;

Fig. 2 is an elevation on a reduced scale;

Fig. 3 is a similar view illustrating the parts positioned for the removal of a bulb;

30 Figs. 4, 5, 6 and 7 are detail views of parts of my invention; and

Fig. 8 is a sectional plan view, the section being taken on a line 8—8 in Fig. 1.

In the drawing a standard socket is indicated by 9 having the usual threaded bushing 10, insulating sleeve 11 and casing-member 12. One of the elements of my invention consists of a threaded plug 13 to engage the bushing 10 of the socket 9, said plug 13 carrying heads 35 14 and 15 of insulating material, through which a conducting post 16 passes. Between the heads 14 and 15, I place a separator 17 and between the head 15 of the plug and head 18 of the post 16, I also place a 40 separator 19. A further element of the invention consists of a threaded sleeve 20 to engage the plug 13; said sleeve or socket member carries the bulb indicated by 21.

The bulb and sleeve 20 preferably tightly 45 engage each other for a purpose to be described. In other words, there will not be any looseness upon the part of the engagement of said parts, and hence the sleeve 20 will have to be held while the bulb is being 50 removed or applied thereto. The sleeve 20 is preferably provided with stops 22 to en-

gage the plug end of the bulb to limit the inward position of same. The sleeve 20 carries a head or flange 23 of insulating material, for a purpose to be described, said 50 head or flange being knurled at the periphery thereof, as indicated by 24. The sleeve or supplemental socket 20 is inclosed by a casing 25 secured at its upper end to a head 26, which in turn is secured to the sleeve 13 65 in any desirable manner, said casing being secured to said head by screws 27 or otherwise. The casing 25 is insulated from sleeve or socket 20 by means of a lining 28 of insulating material. The casing 25 and lining 28 are provided with alining openings 29 and 30 large enough for the passage of the tips of the fingers therethrough. The device also includes an outer casing 31, the function of which is to cover openings 29 70 and 30 after a bulb has been installed to prevent the removal of the bulb. To retain the outer casing 31 in position to cover the openings 29 and 30, I provide a channel-ring 32 which, in this instance, is split and secured 75 to the casing portion of the socket 9 by a binding-screw 33^a. After the outer casing has been moved up to cover openings 29 and 30, the screw 33^a, which is carried by a flange 34 on the outer casing 31, will be 80 screwed in, to engage the channel 35 in ring 32. After screw 33^a engages the channel 35, the outer casing cannot be moved. The screw 33^a will be specially made, requiring 85 a special instrument to operate same, and as there are numerous devices, of this nature, I have not given a detailed description or 90 illustration of same.

To assemble the device, the supplemental 95 socket or sleeve 20 will be placed in the casing 25, the insulating lining 28 having been previously placed in said casing. The casing 25 will now be slipped over end of plug 13 and secured to the flange 26 carried by said plug. This unit will now be applied to 100 the socket sleeve 10, or in other words, the upper end of plug 13 will be screwed into said sleeve as far as it will go. The outer casing 31 may now be applied or slipped over inner casing 25. The openings 29, 30 105 and 41 will now be caused to aline and the flange 23 grasped by the fingers to hold same while a bulb is being applied to the supplemental socket 20. After the bulb has been applied, the socket 20 will be moved up to 110 engage plug 13. After the plug has been screwed up far enough to cause the bulb to

make contact with the conductor 16 the outer sleeve 31 can be secured to ring 32, causing opening 41 to be moved out of alignment. The casing 25 will be deep enough to provide a space 38, after it has been positioned on sleeve 13, between its shoulder 39 and lower edge 40 of the plug 13, slightly deeper than the thickness of the head 23.

It will be seen that the casing 25 is reduced 10 in diameter to form a neck 42 slightly larger than the supplemental socket 20, but smaller than the body of the sleeve, thereby producing the said shoulder 39. The head 23 of the socket 20 is slightly smaller than the 15 body of its casing, but larger than the neck 42; hence said socket 20 cannot be removed from the casing when said casing is installed. The socket 20 may be unscrewed from sleeve 13 to the dotted line position 20 illustrated in Fig. 1, but the bulb cannot be removed therefrom because the head 23 cannot be grasped, as the openings 41, 29 and 30 are not in alignment. The bulb 21 will fit the socket 20 tight enough to prevent 25 its removal unless the head 23 is held. If the head is not held, the bulb and its socket will rotate together. To remove the bulb from the socket 20, the screw 33^a will be unscrewed to release the casing 31, which 30 can be lowered to cause openings 41, 29 and 30 to align, after which head 23 can be held and the bulb removed. Should the socket 20 be unscrewed at any time, the head 23 will drop upon shoulder 38, hence is free to 35 rotate without resistance. When outer casing is in position, the inner casing 25 cannot be removed, as is evident from an inspection of Fig. 1. The outer casing 31 prevents the entire device from being manipulated for the purpose of separation.

Having described my invention, what I claim is:

1. In combination with a standard socket for electric light bulbs, a plug to engage the 45 threaded bushing of said socket, a casing engaging said plug intermediate the ends thereof, a threaded sleeve engaging that portion of the plug which projects into said casing arranged to have screwed into the 50 lower end thereof the threaded end of an electric light bulb, said casing being provided with openings for the passage of the fingers to grasp said threaded sleeve to hold same while a bulb is being applied to or 55 detached therefrom and means carried by the standard socket to cover said opening to prevent the detachment of a bulb.

2. In combination with a standard socket for electric light bulbs, a plug to engage said 60 socket, a sleeve to engage said plug, arranged to have screwed thereinto the threaded end of an electric light bulb, means to cause the threads of the bulb and sleeve to jam to produce a tight fit, a casing in- 65 closing said sleeve having an opening for

the passage of the fingers to grasp said sleeve to prevent the rotation of same while a bulb is being applied to or detached therefrom, means to cover said opening, and means to lock the covering means for said 70 opening.

3. In combination with a standard socket for electric light bulbs, a plug to engage said socket, a sleeve to engage said plug, arranged to have screwed thereinto the 75 threaded end of an electric light bulb, means to cause the threads of the bulb and sleeve to jam to produce a tight fit, a casing in- closing said sleeve having an opening for the passage of the fingers to grasp said 80 sleeve to prevent the rotation of same while a bulb is being applied to or detached therefrom, an outer casing applied to the casing first named, having an opening to align with the opening in the casing first named, ar- 85 ranged to be moved to cause its opening to be carried out of alignment with the opening in the casing first named, and means to lock the outer casing to the socket.

4. In combination with a standard socket 90 for electric light bulbs, a plug to engage said socket, a sleeve to engage said plug ar- ranged to have screwed thereinto the threaded end of an electric light bulb, means to cause the threads of the bulb and sleeve 95 to jam to produce a tight fit, a casing in- closing said sleeve having an opening for the passage of the fingers to grasp said sleeve to prevent the rotation of same while a bulb is being applied to or detached there- 100 from, an outer casing applied to the casing first named, having an opening to align with the opening in the casing first named, ar- ranged to be moved to cause its opening to be carried out of alignment with the opening in the casing first named, a channelled 105 ring carried by the socket, and a screw carried by the outer casing to engage the channel in said ring.

5. In combination with a standard socket 110 for electric light bulbs, a plug to engage the threaded bushing thereof, a head engaging said plug intermediate the ends thereof, a sleeve engaging that portion of the plug which projects through said head, arranged 115 to receive an electric light bulb, a casing secured at one end thereof to said head, said casing being reduced in diameter throughout a portion of its length to provide a neck slightly larger in diameter than said sleeve, 120 a flange carried by said sleeve located within the larger part of the casing which incloses the sleeve, said flange being larger in diameter than said neck, said casing being provided with openings for the passage of 125 the fingers to grasp the flange carried by said sleeve, a movable outer casing covering the larger part of the inner casing and ar- ranged to engage same, said outer casing being provided with openings to align with 130

- the openings in the inner casing, said openings being out of alinement excepting when a bulb is to be applied or removed, and means to lock the outer casing to the socket.
- 5 6. In combination with a standard bulb-socket, a plug to engage the threaded bushing thereof, a threaded sleeve to engage the threaded end of the bulb removably supported thereby, a casing inclosing said sleeve and having a shoulder, and a flange carried
- by the sleeve adapted to rest upon said shoulder and to freely rotate thereupon when the sleeve is disengaged from the plug.
- Signed at New York city, N. Y., this 8 day of May, 1919.

SAMUEL L. ADELSON.
